FIGURE 1 is a perspective view of an electrical transformer or similar article showing my new design;

FIGURE 2 is a front elevational view, the rear view being substantially a mirror image thereof;

FIGURE 3 is a side elevational view, the opposite side being substantially a mirror image thereof; and

FIGURE 4 is a top plan view thereof.

The bottom, not shown, is a conventional substantially flat unornamented surface. The dominant features of the design reside in the portions shown in full lines and in the terminal arrangement wherein each of the terminals are symmetrically disposed the sides of the transformer and have an oval indentation at the base thereof as shown.

I claim:

The ornamental design for an electrical transformer or similar article, as shown and described.
